Roswell Wilkin
Witnesses Patent

The following is a record of witness to the said Patent, and containing parts
of the same, contains a description in the words of the said Ros-
well Wilkin himself of his method of manufacturing hats, &c. by
scraping them from fleece or sheet taken from a carding
engine without bawling.

The materials to be wrought into hats, spreads, &c. are prepared on
a carding machine as is common use in cotton factories, and
the fleece or sheet formed on the down cylinder is to be used &
applied in the manner following, viz.

When the fleece is taken from the cylinder it is to be spread
out, and upon the fleece and upon the fleece, or sheet there
are laid patterns of various forms, such as circular, triangular
conical &c. according to the fashion and size of the hat or other
article to be made, and pieces of various sizes, shapes
and dimensions, are to be taken out of the fleece or sheet suit-
able to form the hat, or other article intended to be made
together with pieces for bands, stiffings, &c. whose pieces or
shapes are to be wrought together by placing them in order with
suitable attention to the grain, and pressing, rolling and moving
them upon a plate or plates, heated and prepared, by which
operation or process they are unit'd to each other into the proper
shapes or bodies for the purposes aforesaid, and are then to
be reduced to sufficient firmness by bawling, planking &c ac-
cording to art.
